Hamilton Sanders LLP; Ryan Schneider; Chris N. Davis(57) **CLAIM**

The ornamental design for a measuring scoop, as shown and described.

DESCRIPTION

FIG. 1 is a top perspective view of the measuring scoop;
 FIG. 2 is a top view of the measuring scoop;
 FIG. 3 is a left side view of the measuring scoop;
 FIG. 4 is a bottom view of the measuring scoop;
 FIG. 5 is a right side view of the measuring scoop;
 FIG. 6 is a front view of the measuring scoop; and,
 FIG. 7 is a rear view of the measuring scoop.
 The broken lines illustrate a portion of the measuring scoop
 that forms no part of the claimed design.
